UNITED STATES PATENT OFFICE.

MAGNUS UNGER, OF PITTSFIELD, MASSACHUSETTS, ASSIGNOR TO GENERAL ELECTRIC COMPANY, A CORPORATION OF NEW YORK.

INDUCTION-FURNACE.

941,435.

Specification of Letters Patent. Patented Nov. 30, 1909.

Application filed May 6, 1908. Serial No. 431,138.

To all whom it may concern:

Be it known that I, MAGNUS UNGER, a subject of the King of Sweden, residing at Pittsfield, county of Berkshire, State of 5 Massachusetts, have invented certain new and useful Improvements in Induction-Furnaces, of which the following is a specification.

My invention relates to electric furnaces 10 of the type known as induction furnaces, which are used for metallurgical purposes. Furnaces of this type, in general, comprise a magnetic core and primary winding upon this core, and a furnace chamber placed in 15 inductive relation to the primary, so that the charge will serve as a secondary, that is, the magnetic flux threading through the charge will induce currents in the same.

In furnaces as heretofore built the size of 20 the secondary (that is, the quantity of charge) cannot be increased without greatly reducing the power factor unless the frequency is very low. This, of course, is due to the fact that as the size of the charge 25 increases there is a large stray field, which results in a low power factor according to well-known electrical principles. To run the furnace at very low frequencies requires special installations, and such special installations are very costly. Moreover the power 30 factor cannot be improved sufficiently by this means when the size of the furnace exceeds certain limits, or when the specific resistance of the charge is low.

The furnace which forms the subject of 35 the present invention is so constructed that a current from a single-phase, or a polyphase source, may be used for its operation and not only the advantage incident to using 40 currents from ordinary commercial installations is gained, but also a very marked improvement in power factor. Besides this, my furnace has a better thermal efficiency than furnaces as built heretofore. Other advantages, such as convenience of charging 45 and flexibility of voltage, will be hereinafter further pointed out.

Figure 1 shows the furnace in perspective; Fig. 2 is a plan view of the furnace, showing 50 also current connections to a polyphase system; and Fig. 3 shows the connections to be used with a single-phase source of energy.

Fig. 1 shows a furnace of the tilting type with a furnace 1 set upon a base plate 2. 55 As shown in both Figs. 1 and 2, the furnace

has two sets of primary windings 3 and 4, wound upon cores 5 and 6. Surrounding these primary windings is the furnace chamber 7 inclosed in fire-brick walls 8. An alternating current passing through the primary windings 3 induces a current in a charge placed in the furnace chamber according to well-known principles. The fluid metal or flux may be tapped off through the spout 10. As shown in the figure, the annular furnace 60 chambers interlink to form a central space, which, as will be pointed out, forms a most convenient treating chamber. As the annular channels surrounding the primary cores may be made of comparatively small 65 cross-section without sacrificing the capacity of the furnace, the resistance at these regions will be correspondingly high, thus keeping a high power factor, and at the same time 70 making a furnace of larger capacity than it is now possible to operate with commercial frequencies. As there will be practically no current in the center of the furnace, the furnace chamber is made shallower at this point by the projection 9. However, the 75 central chamber holds a considerable amount of the charge, which is protected in this way from excessive radiation, and the furnace has, therefore, a high thermal efficiency.

A point not to be overlooked is that the 80 central space may be used for the introduction of comparatively large blocks of raw material, either ore or flux. As the size of the furnace chamber is confined within narrow 85 limits this matter of convenience of charging forms an important item in the construction of furnaces of this kind. The central space may be used for the refining of metals, in a manner similar to the open-hearth 90 process.

The furnace is shown in Fig. 2 connected to a transformer supplied with three-phase currents in its primary coils 11, which are T-connected and deliver two-phase currents 95 in the secondaries 12. With proper connections in the manner well understood by those skilled in the art, the furnace may be operated on any polyphase system. The two units shown, or any number of units may be 100 operated in parallel on a single-phase system, as illustrated by Fig. 3, in which the primary windings 3, 4 are connected in parallel to a single-phase source of energy 13, by conductors 14, 15 respectively. It will 105 be seen that this type of furnace possesses a 110

flexibility of voltage not possible with other types of single-phase or polyphase furnaces.

What I claim as new and desire to secure by Letters Patent of the United States, is

- 5 1. In an induction furnace, the combination of a plurality of magnetic cores, windings upon said cores, and a plurality of annular furnace chambers surrounding said cores and communicating with a shallow central chamber.
- 10 2. In an induction furnace, the combination of a plurality of magnetic cores, independent primary windings upon said cores, and a central treating chamber surrounded by narrow segmental annular chambers opening into said central chamber and in in-

ductive relation with said primary windings.

3. The combination of a plurality of magnetic cores forming closed magnetic circuits, 20 independent primary windings upon each of said cores, a single source of energy for said windings, and a plurality of intercommunicating charges in inductive relation to said magnetic circuits. 25

In testimony whereof, I have hereunto set my hand this fourth day of May, 1908.

MAGNUS UNGER.
